(57) **ABSTRACT**

A pet travel door system may include a door having an integrated pet travel door. The door may include a main body member having a door panel. A passageway may be formed in the door panel. A recess may be formed within the top and/or the bottom of the passageway. The system may include a structural member matingly engaged with the recess and a U-shaped structural member that overlies the recess having the structural member matingly engaged thereto. The structural member and the U-shaped structural member may have a through channel formed through a portion thereof. The main body member may have a respective receiving channel formed therein. The through channels formed in the structural member and the U-shaped structural member may be positioned to align with one another and with the respective receiving channel formed in the main body member.

PET TRAVEL DOOR SYSTEM**FIELD OF THE INVENTION**

The present invention relates to systems for easily installed secure pet doors with a security panel to prevent unwanted entry along with sealing the pet door from extreme weather conditions and withstanding impacts from airborne objects.

BACKGROUND OF THE INVENTION

In areas that are subject to extreme weather conditions there is a need for a pet door that has the functionality to be sealed closed to prevent the weather from passing through the pet door which includes a seal that reduces and prevents wind, water, ice, and flying objects from passing through the pet door. There is also a need in areas subject to chances of unwanted entries to be able to seal the pet door shut in order to mitigate the chances of an unwanted entry taking place through the pet door.

The prior art does not address these problems effectively and only address the problems of providing security against unwanted entries and preventing only mild to moderate weather conditions from getting past the pet door. The structure and anchoring of the prior art is lacking the ability to prevent extreme weather conditions and airborne object impacts at high speeds from entering through the pet door. The prior art also does not address the above issues to the degree of achieving relevant structural and impact ratings for hurricane sever weather conditions along with mitigating unwanted entries by intruders. Therefore, there is a need for a pet door which can be easily installed and sealed shut to prevent unwanted entries, extreme weather conditions, and flying objects from entering through the pet door that is also up to standard for relevant structural and impact ratings for hurricane sever weather conditions to provide for increased safety and security of users.

This background information is provided to reveal information believed by the applicant to be of possible relevance to the present invention. No admission is necessarily intended, nor should be construed, that any of the preceding information constitutes prior art against the present invention.

SUMMARY OF THE INVENTION

With the above in mind, embodiments of the present invention are related to a pet travel door system. The pet travel door system according to the present invention may be defined by an embodiment including a door having an integrated pet travel door. The pet travel door system according to the present invention may also be defined by an embodiment including a door panel having an integrated travel door that may be configured to be inserted into a door. The pet travel door system according to the present invention may further be defined by a kit for retrofitting an existing door with a pet travel door.

The pet travel door system, in one embodiment, may include a door having an integrated pet travel door. The door may include a main body member, a structural member, and a U-shaped structural member. The main body member may have a door panel located thereon and a passageway formed in the door panel. The passageway may include a recess formed at the top and/or bottom in it that may be adapted to accept the placement of the structural member within it. The U-shaped structural member may also be placed overlaying

the structural member and the recess. The structural member and U-shaped structural members may include one or more through channels formed through a portion of them. The main body member may also include receiving channels formed at the top and/or bottom of the passageway that are adjacent to and match the placement of the through channels on the structural members and the U-shaped structural members. The through channels formed in the structural members and the U-shaped structural member may also be positioned to align with each other and the receiving channels formed in the main body member.

The structural member and the U-shaped structural member may be secured to the recess using either adhesive and/or double-sided adhesive tape. The system may further include a pet travel door having a pet travel door frame that is attached to the door panel. The pet travel door frame may have a shape that is substantially similar to the shape of the passageway formed in the panel. The pet travel door frame may be secured to the door panel adjacent to the top, bottom, and/or side portions of the passageway using screws and/or bolts. The screws and/or bolts may be placed so that they may be only accessible from one side of the door panel.

The system may include a security panel that is configured to cover the pet travel door. The security panel may include a security panel body member, a lower security panel structural member, and a pair of structural post members. The lower security panel structural member may be connected to a bottom portion of the security panel member, and the pair of structural post members may be connected to a bottom portion of the lower security panel structural member and extending outwardly therefrom.

The system may further include a lock member that is carried by a top portion of the security panel body member with the lock member being rotatably moveable between a locked position and an unlocked position. The lock member may include a locking arm, where the locked position of the lock member may be defined as the locking arm of the lock member being positioned to engage a lock slot formed in a portion of the door panel adjacent to the top of the passageway, and the unlocked position of the lock member may be defined as the locking arm being positioned to disengage the lock slot formed in the door panel.

The security panel may include an upper security panel structural member that may be fixed to the top of the security panel body member. Where the upper security panel structural member may have an upper security panel lock slot formed therein and that may be positioned to align with the lock slot formed in the door panel.

The system may include a seal member that may be positioned adjacent the outer peripheral portion of the security panel body member. The seal member may have a lock slot formed therein that may be positioned to align with the lock slot formed in the door panel.

The lock member may include a key lock that is moveable between unlocked and locked positions. When the key lock is in the locked position, the lock member may not be moveable between locked and unlocked positions, and when the key lock is in the unlocked position, the lock member may be moveable between locked and unlocked positions.

Another embodiment of the pet travel door system according to the present invention is directed to a door panel having an integrated pet travel door. The door panel may include a body member that may include a front face and a back face. The pet travel door may be carried by the body member. The door panel may also include a body frame member affixed to the to the body member. A passageway

may be formed in the body member, and may be defined as having a top, a bottom, and side portions extending between the top and the bottom.

A recess may be formed within the top and/or the bottom of the passageway of the body member. The door panel may also include a structural member matingly engaged with the recess, and a U-shaped structural member that overlies the recess having the structural member matingly engaged thereto. The structural member and the U-shaped structural member may have a through channel formed through a portion thereof. The body member may have a respective receiving channel formed therein adjacent to the top and/or the bottom of the passageway. The through channels formed in the structural member and the U-shaped structural member are positioned to align with one another and with the respective receiving channel formed in the body member.

Another embodiment of the pet travel door system according to the present invention is directed to a kit to retrofit an existing door to include a pet travel door. The kit may include a container, a pet travel door carried by the container, and a structural member carried by the container. The kit may also include a U-shaped structural member carried by the container, and at least one of an adhesive, an adhesive double sided tape, at least one screw, and at least one bolt carried by the container. The pet travel door may be adapted to be affixed within a passageway formed through a portion of the existing door. The pet travel door may also be adapted to be affixed within the passageway using at least one of the adhesive, the adhesive double-sided tape, the at least one bolt, and the at least one screw.

BRIEF DESCRIPTION OF THE DRAWINGS

Some embodiments of the present invention are illustrated as an example and are not limited by the figures of the accompanying drawings, in which like references may indicate similar elements.

FIG. 1A is a perspective view of a door having an integrated pet travel door according to an embodiment of the present invention and having a security panel installed.

FIG. 1B is a perspective view of the door illustrated in FIG. 1A and having the security panel removed.

FIG. 2 is a perspective view of a door panel having a pet travel door installed therein and being installed in a door according to an embodiment of the present invention.

FIG. 3 is a perspective view of the door panel illustrated in FIG. 2 being separated from the door.

FIG. 3A is a perspective view of the door panel illustrated in FIG. 3 having the pet travel door removed to show a passageway.

FIG. 4 is perspective view of an embodiment of the pet travel door of the door panel illustrated in FIG. 3.

FIG. 5 is a perspective view of a security panel of the pet travel door according to an embodiment of the present invention and showing a lock member in the locked position.

FIG. 6 is a rear perspective view of the security panel of FIG. 5.

FIG. 7 is an upper perspective view of the security panel of FIG. 5.

FIG. 8 is a perspective view of a lock member of the security panel illustrated in FIG. 5.

FIG. 9 is a lower perspective view of the security panel according to FIG. 5.

FIG. 10 is a perspective view of structural members and a lock member that connect to the security panel illustrated in FIG. 5.

FIG. 11A is a plan view of a bottom seal member adapted to be connected to the security panel of FIG. 5.

FIG. 11B is a plan view of a top seal member adapted to be connected to the security panel of FIG. 5.

FIG. 12 is a lower perspective view of a pet travel door frame of the pet travel door according to an embodiment of the present invention.

FIG. 13 is a side elevation view of an embodiment the seal member illustrated in FIGS. 11A and 11B.

FIG. 14 is a side elevation view of another embodiment the seal member illustrated in FIGS. 11A and 11B.

FIG. 15A is a partial perspective view of a structural member, a U-shaped structural member, and a lower portion of a body member or door panel according to an embodiment of the present invention.

FIG. 15B is a partial perspective view of a structural member, a U-shaped structural member, and an upper portion of a body member or door panel according to an embodiment of the system.

FIG. 16A is a partial perspective view of the U-shaped structural member illustrated in FIG. 15A being placed over the structural member and body member or door panel.

FIG. 16B is a partial perspective view of the U-shaped structural member illustrated in FIG. 15B being placed over the structural member and body member or door panel.

FIG. 17A is partial perspective view of the structural member illustrated in FIG. 15A being positioned in a recess formed in the lower portion of the body member or the door panel.

FIG. 17B is a partial perspective view of the body member or the door panel according to an embodiment of the present invention showing the recess formed therein.

FIG. 18A is a partial perspective view of the U-shaped structural member illustrated in FIG. 15A and being positioned over the structural member and the lower portion of the body member or the door panel.

FIG. 18B is a partial perspective view of the U-shaped structural member illustrated in FIG. 15B and being positioned over the structural member and the upper portion of the body member or the door panel.

FIG. 19 depicts a kit to retrofit an existing door with a pet travel door according to embodiments of the present invention.

FIG. 20 is a perspective view of the lock member in FIG. 8 that does not include a key lock.

FIG. 21 is a perspective view of the components of the security panel illustrated in FIG. 10 connected together as a monolithic unit.

FIG. 22A is a partial perspective view of a U-shaped structural member being positioned over a lower portion of the body member or door panel according to the present invention without a structural member.

FIG. 22B is a partial perspective view of a U-shaped structural member being positioned over an upper portion of the body member or door panel according to the present invention without a structural member.

FIG. 23A is a perspective view of a hingedly connected security panel to be used in connection with the pet travel door system according to an embodiment of the present invention and in a closed position.

FIG. 23B is a perspective view of the security panel of FIG. 23A in an open position.

FIG. 23C is a side perspective view of the security panel illustrated in FIG. 23B.

FIG. 24 is a perspective view of a hingedly connected security panel attached to a pet travel door carried by a door panel according to an embodiment of the present invention and in an open position.

DETAILED DESCRIPTION OF THE INVENTION

The present invention will now be described more fully hereinafter with reference to the accompanying drawings, in which preferred embodiments of the invention are shown. This invention may, however, be embodied in many different forms and should not be construed as limited to the embodiments set forth herein. Rather, these embodiments are provided so that this disclosure will be thorough and complete, and will fully convey the scope of the invention to those skilled in the art. Those of ordinary skill in the art realize that the following descriptions of the embodiments of the present invention are illustrative and are not intended to be limiting in any way. Other embodiments of the present invention will readily suggest themselves to such skilled persons having the benefit of this disclosure. Like numbers refer to like elements throughout.

Although the following detailed description contains many specifics for the purposes of illustration, anyone of ordinary skill in the art will appreciate that many variations and alterations to the following details are within the scope of the invention. Accordingly, the following embodiments of the invention are set forth without any loss of generality to, and without imposing limitations upon, the claimed invention.

In this detailed description of the present invention, a person skilled in the art should note that directional terms, such as "above," "below," "upper," "lower," and other like terms are used for the convenience of the reader in reference to the drawings. Also, a person skilled in the art should notice this description may contain other terminology to convey position, orientation, and direction without departing from the principles of the present invention.

Furthermore, in this detailed description, a person skilled in the art should note that quantitative qualifying terms such as "generally," "substantially," "mostly," and other terms are used, in general, to mean that the referred to object, characteristic, or quality constitutes a majority of the subject of the reference. The meaning of any of these terms is dependent upon the context within which it is used, and the meaning may be expressly modified.

An embodiment of the invention, as shown and described by the various figures and accompanying text, provides a reinforce pet door system that may include a pet travel door 301, illustratively shown in FIGS. 3 and 4, a door panel 303 with an integrated pet travel door 301, illustratively shown in FIG. 3, and a security panel 502 as illustratively shown in FIG. 5. The pet travel door 301 may comprise of a number of different types of pet travel doors, for example, without limitation, sliding, single flap, partitioned flap, magnetized bottom flap, magnetized sliding, or other pet travel door as understood by those skilled in the art that may be used. The pet travel door 301 may comprise of a number of different materials including, but not limited to, polycarbonate, plastic, metal, or ceramic. Those skilled in the art will notice and appreciate that a number of different pet travel doors and materials may be used as the pet travel door 301 while still accomplishing all the goals, features, and advantages of the present invention.

Referring initially to FIGS. 1A and 1B, an embodiment of the pet door system according to the present invention is

now described. This embodiment of the pet door system is directed to a door 100 having an integrated pet travel door 301. The integrated pet travel door 301 is preferably configured to be installed into a main body member 101 of a door 100. The main body member 101 may include a number of door panels 105 where the pet travel door 301 may be installed into. The pet travel door 301 is preferably installed in the lowest door panel 105 of the main body member 101, as illustrated in the appended drawings. Those skilled in the art, however, will appreciate that should it be desired, the pet travel door 301 may be installed anywhere on the main body member 101 of the door 100. For example, if so desired, the pet travel door may be installed on an upper panel of the door 100, or off set from a central vertical line of the door. However, it is preferable, from both a functional and an aesthetic perspective, to provide the pet travel door 301 installed in the lower panel 105 of the main body member 101 of the door 100.

Now referencing FIGS. 2, 3, and 3A, another embodiment of the present invention directed to a door panel 303 having an integrated pet travel door 301 installed therein. The door panel 303 having the integrated pet travel door 301 installed therein may be provided to be installed into a door. For example, a door manufacturer may install the door panel 303 having the integrated pet travel door 301 into an existing door where a panel 105 may have been otherwise located.

The pet travel door 301 may be installed into a body member 201 of the door panel 303. The body member 201 of the door panel 303 that has the pet travel door 301 installed therein may be installed into a main body member 101 of a door 100 that has a portion or all of one of its door panels 105 removed. Those skilled in the art will appreciate that it contemplated that the door panel 105 may be removed after manufacture of the door 100 to allow for installation of the door panel 303 in the door 100, or that the door 100 may be manufactured without the door panel 105 to similarly allow for installation of the door panel 303 having the integrated pet door 301 according to the present invention. The main body member 101 that the body member 201 is installed into may not require that a door panel 105 is removed and may only require removing a portion of the main body member 101 so that the door panel 201 may be matingly installed into the main body member 101. Those skilled in the art will also appreciate that the door panel 303 having the integrated pet travel door 301 may also be installed into a door 100 that does not include door panels. In such a case, it is contemplated that a passageway will be formed in the door 100 to accommodate installation of the door panel 303 having the pet travel door 301 integrated therein. The body member 201 may comprise of a number of different insulating and non-insulating materials. The insulating materials that may be used as the body member 201 may be, without limitation, fiberglass, expanded polystyrene, polyurethane, mineral wool, cellulose, E-glass reinforced fiberglass, S-glass reinforced fiberglass, aramid reinforced fiberglass, carbon reinforced fiberglass, and other materials as recognized by those skilled in the art to be used as and/or in the body member 201 of an embodiment of the present invention.

Moreover, as mentioned further below, the body member 201 may comprise of a door panel that was cut out of a door during the manufacturing process of said door. Door panels that are cut out of a door during the manufacturing process are generally discarded and eventually located in a land fill with other construction waste and debris. The present invention can advantageously repurpose that which would have been wasted or environmentally unfriendly trash/debris, and

using it to carry out the goals, features and advantages of the present invention. Therefore, the present invention is environmentally friendly and helps to reduce waste.

Continuing to reference FIG. 3A, the door panel 105 that is a separate object from a main body member 101 (such as body member 201), or a door panel that is monolithically formed a part of a main body member 101 (such as one of the door panels 105 in the main body member 101 as illustratively shown in FIGS. 1A and 1B) may include a passageway 304 that is formed through one face of the body member 201 (or door panel 105) and out an opposite side/face. The passageway 304 may be sized to accommodate the size of the pet travel door 301.

Continuing with reference to FIGS. 2, 3 and 3A, the door panel may include body frame members 202. The body frame members 202 may be affixed to an outer perimeter of the body member 201 of the door panel 303, and on a perimeter of the passageway 304 of a main body member 101. The passageway 304 may be configured to be a shape that may accommodate installation of the body member 201 that has the body frame members 202 affixed onto the outer perimeter of the body member 201. The body frame members 202 may be used to provide a seal when the door panel 303 is installed into the main body member 101 of the door 100 to advantageously protect an interior of a structure from elements of weather, such as wind, water, and ice. The body frame members 202 may be made from steel, aluminum, plastic, composite, ceramics, or any other material or combination thereof as understood by those skilled in the art that may be used as a body frame members 202. Those skilled in the art will notice and appreciate that a number of different materials may be used for the body frame member 202 while still accomplishing all the goals, features, and advantages of the present invention.

FIG. 4 depicts an alternative pet travel door 301 that may be used in connection with the present invention. The pet travel door 301 illustrated in FIG. 4 illustratively includes a segmented door 310. The segmented door 310 illustratively includes three segments. The three segments of the segmented door 310 are independently moveable with respect to one another. Accordingly, this may be advantageous for smaller animals that use the pet travel door 301. The pet travel door 301 illustrated in FIG. 4 also includes framing 302 that is described in greater detail below.

Now referring back to FIGS. 1A, 1B, and further to FIGS. 4 and 12, a pet travel door 301 may include a pet travel door frame 302 that may be affixed to an outer perimeter of the pet travel door 301 and affixed to the passageway 304 that may be made in a body member 201 or a main body member 101. The pet travel door frame 302 may include a pet travel door frame lock slot 1203 that is located at an upper portion of the pet travel door frame 302. The pet travel door frame 302 may also include one or more pet travel door frame through channels 1202 that may be located at a lower portion of the pet travel door frame 302. The pet travel door frame 302 may be made from plastic, composite, aluminum, steel, or any other material as understood by those skilled in the art to be used as a pet travel door frame 302. Those skilled in the art will notice and appreciate that a number of different materials may be used as the pet travel door frame 302 while still accomplishing all the goals, features, and advantages of the present invention.

Now referencing FIGS. 5-9, an embodiment of the present invention may include a security panel 502. The security panel 502 may be adapted to cover the pet travel door 301 on the outdoor and/or the indoor facing side of the pet travel door 301. The security panel 502 may be adapted to cover

the pet travel door 301 by placing the security panel 502 overlaying the pet travel door 301. The security panel 502 may include a lock member 104, a pair of post structural members 901, a number of seal members 501, a security panel body member 102, and a reinforcement panel 602. The security panel body member 102 may be a cutout of a door panel from a door, such as door panels removed from doors during the manufacturing process of the door that otherwise would be treated as a waste product may instead be repurposed to be used as the security panel body member 102 or the body member 201 for an embodiment of the present invention. Those skilled in the art will appreciate that this act of recycling decreases the environmental impact of the door manufacturing process and decreases the cost of creating an embodiment of the present invention. The security panel body member 102 may comprise of insulation materials to increase the security panel's 502 effectiveness at reducing elements of weather from passing through an embodiment of the present invention. The material of the security panel body member 102 may comprise of structural fiberglass such as, without limitation, E-glass reinforced fiberglass, S-glass reinforced fiberglass, aramid reinforced fiberglass, and carbon reinforced fiberglass or any material as understood by those skilled in the art that may be used as the security panel body member 102. Those skilled in the art will notice and appreciate that the security panel body member 102 may comprise of a number of different materials while still accomplishing all the goals, advantages, and goals of the present invention.

The reinforcement panel 602 may be affixed to a face on the security panel body member 102, preferably a back-side face of the security panel body member 102. The material used for the reinforcement panel 602 may be, without limitation, polycarbonate. Those skilled in the art will recognize that the reinforcement panel 602 may comprise of a number of different materials while still accomplishing all the goals, features, and advantages of the present invention. The reinforcement panel 602 may be adapted to cover the same area as the face of the security panel body member 102 that the reinforcement panel 602 is attached to. Those skilled in the art will appreciate that the frame 302 of the alternative pet travel door 301 illustrated in FIG. 4 may also be made of a polycarbonate material to provide enhanced reinforcement.

The lock member 104 may be carried by a front face of the security panel body member 102, and preferably at a top portion of the front face of the security panel body member 102. The lock member 104 may include a locking arm 601 that may be attached to the lock member 104. The lock member 104 may be rotatably movable between a locked position and an unlocked position. The locked position of the lock member 104 may be defined by the locking arm 601 being positioned to extend outwardly, from the door and to engage a security panel body member lock slot 701 (discussed in greater detail below). The unlocked position of the lock member 104 may be defined by the locking arm 601 being rotatably positioned so as not to engage the security panel body member lock slot 701.

Those skilled in the art will notice and appreciate that a number of different types of locks may be implemented as the lock member 104 while still accomplishing all the goals, features, and advantages of the system. For example, without limitation, a padlock, a deadbolt, a lever handle, a cam lock, a euro profile cylinder, a mortise lock, a T-handle lock, a rim latch lock, a multi-point lock, a key-operated security lock, a closed shackle lock, a straight shackle lock, an open shackle padlock, a long shackle padlock, electronically

operated locks, and many other lock types known by those skilled in the art may be used as the lock member 104 while still accomplishing all the goals, features, and advantages of the system.

The lock member 104 may include a key lock 801 that is connected to the lock member 104. The key lock 801 may be configured so that when the key lock 801 is in a locked position the lock member 104 is restricted from rotatably moving, and when the key lock 801 is not in the locked position the lock member 104 is unrestricted and is free to rotatably move. The security panel body member 102 may include a security panel body member lock slot 701 that may be configured to allow for movement of the locking arm 601 when the lock member 104 is in the locked and/or unlocked positions. Details for the lock member's 104 locking functions follow further below.

Those skilled in the art will notice and appreciate that a variety of different types of locks may be used as the key lock 801 while still accomplishing all the goals, features, and advantages of the present invention. For example, without limitation, the key lock 801 may comprise of a combination lock, a touchscreen security lock, a proximity signal lock, a deadbolt, a fingerprint reader lock, a remote signal lock, a biometric scanner lock, and/or other types of locks as understood by those skilled in the art.

Embodiments of the present invention may not have a key lock 801 included with the lock member 104. Instead, some embodiments of the present invention may include a key lock 801 that is separate and not connected to the lock member 104. The key lock 801 may instead be carried by the security panel body member 102 and/or the body member 201. A key lock 104 that is not connected to the lock member 104 may include the same features and functionality as a key lock 104 that is connected to the lock member 104 as described herein. An embodiment of the present invention may also not include a key lock 104 as a component of the system so that the lock member 104 is the only component of the system with locking functionality, as illustratively shown in FIG. 20. Such an embodiment of the present invention may be preferable when the embodiment includes a security panel 502 that is installed to cover the indoor facing side of the pet travel door 301.

Now additionally referencing FIG. 10, the security panel 502 may include an upper security panel structural member 1001 and a lower security panel structural member 1003. The upper security panel structural member 1001 may be attached to an upper portion of the security panel body member 102. The upper security panel structural member 1001 may include an upper security panel structural member lock slot 1002 that is positioned to align with and allow for the rotatable movement of the locking arm 601 of the lock member 104.

The lower security panel structural member 1003 may be attached to a lower portion of the security panel body member 102 and may include one or more structural post members 901 (also illustrated in FIG. 9) that may be affixed on a lower surface of the lower security panel structural member 1003 and may be oriented outwards. The structural post members 901 may be affixed to the lower security panel structural member 1003 or a part of the lower security panel structural member 1003 as a single monolithic unit.

The lower security panel structural member 1003 may be in the shape of a "U" and configured to snugly form around the security panel body member 102 when affixed thereto. The lower security panel structural member 1003 may also be split into separate pieces, or the upper security panel structural member 1001 and the lower security panel struc-

tural member 1003 may be connected together as on single monolithic unit as illustratively shown in FIG. 21. Those skilled in the art will recognize and appreciate that there are a number of different shapes and configurations that the upper security panel structural member 1001 and the lower security panel structural member 1003 can include while still accomplishing all the goals, features, and advantages of the present invention.

Continuing with reference to FIGS. 5-10, seal members 501 may be affixed to an outer perimeter of the security panel body member 102 to substantially cover the outer perimeter of the security panel body member 102 and may be positioned to overly the upper security panel structural member 1001 and the lower security panel structural member 1003. Those skilled in the art will notice and appreciate that a number of materials and material combinations can be used for the seal members 501 while still accomplishing all the goals, features, and advantages of the present invention.

The seal members 501 may include a grip member 501a and a sealing lip 501b, as illustratively shown in FIGS. 13 and 14. The grip member 501a may be used to hold the security panel 502 in place when the security panel 502 is installed to cover a pet travel door 301 when the pet travel door 301 is installed into a main body member 101 or a door panel 303. The grip member 501a may also act as an extra layer of sealant to keep weather elements from seeping past the security panel 502 when covering a pet travel door 301. The sealing lip 501b may comprise entirely of, or in part, a flexible material similar to the material that the seal member 501 is made of, in whole or in part. The sealing lip 501b may be used as the main component to seal the elements from passing through the security panel 502 when the security panel is installed covering the pet travel door 301.

The seal members 501 may include, without limitation, a heterogeneous combination of polyvinyl chloride and a flexible material. The flexible material used may be a rubber, plastic, composite, or other material as understood by those skilled in the art to be used as a flexible material that can be used for all or a portion of the seal member 501, the grip member 501a, and/or the sealing lip 501b.

Continuing with reference FIG. 10, and additionally referencing FIG. 11, the seal member 501 that is located at the lower portion of the security panel body member 102 may contain a number of seal member through channels 1103 that are substantially aligned with the placement of the structural post members 901 on the lower security panel structural member 1003. A seal member 501 that may be located at an upper portion of the security panel body member 102 may contain a upper security panel lock slot 1104 that is positioned to align with the locking arm 601 of the lock member 104, and an arched cutout 1102 that may be located on one side of at least one of the seal members 501 that may be configured to accommodate the lock member 104 being carried by the security panel body member 102 without having the lock member 104 be positioned in conflict with the seal member 501 that may be closest to the lock member 104 when the lock member 104 is attached to the security panel body member 102.

Now referring to FIGS. 17A and 17B, an embodiment of the present invention may include a recess 1510 at a lower portion of the passageway 304. In the embodiment of the invention directed to the door 100 having an integrated pet travel door 301 formed therein (illustrated in FIGS. 1A and 1B), the recess 1510 is formed in the body member 101 of the door 100. Although the embodiment of the invention relating to the door 100 having the integrated pet door 301 does not show a passageway prior to the door panel being

11

installed therein is shown, those skilled in the art will appreciate that the recess 1510 is formed in a lower portion of the door panel 105. In the embodiment of the invention directed to a door panel 303 having a pet travel door 301 installed therein that is separated from the door 100 and adapted to be positioned in a space in door 100 where a door panel 105 may have otherwise been located (illustrated in FIGS. 2, 3 and 3A), the recess 1510 may be formed in the body member 201 of the door panel 303.

As also illustrated in FIGS. 17A and 17B, one or more receiving channels 1512 may be provided to receive the structural post members 901. Within the recess 1510 there may be a structural member 1501 that is matingly engaged within the recess 1510. On the structural member 1501 there may be one or more structural member through channels 1503 that may be positioned to align with the receiving channels 1512 on the recess 1510.

As illustrated in FIG. 18A, the U-shaped structural member 1502 may be placed to overly the structural member 1501 and the recess 1510. The U-shaped structural member 1502 may include one or more U-shaped structural member through channels 1504 (illustrated in FIG. 16A) that may be positioned to align with the structural member through channels 1503 and the receiving channels 1512.

Now referring back to FIGS. 15B and 17B, at an upper portion of the passageway 304 that is in either the body member 201 or the door panel 105, there may be a recess 1510 that accepts the mating placement of a structural member 1501. Referring to FIG. 16B, the structural member 1501 may include a lock slot 1601 that may be configured to accept the engagement of the locking arm 601 when the lock member 104 is engaged. There U-shaped structural member 1502 may also include a structural member lock slot 1505 that may be configured to align with the structural member lock slot 1601 on the structural member 1501 that is placed in the recess 1510 at the upper portion of the passageway 304 of either the body member 201 or a door panel 105. The U-shaped structural member 1502 may be positioned to matingly engage and overly the structural member 1501, as illustratively shown in FIGS. 16B and 18B. The U-shaped structural member lock slot 1505 and the structural member lock slot 1601 may be positioned to align with one another.

Now referencing FIGS. 22A and 22B, an embodiment of the present invention may not include a structural member 1501 and may only include a U-shaped structural member 1502 that may be adapted to be matingly placed to overly a lower portion or an upper portion of the body member 201. If only a U-shaped structural member 1502 is used, those skilled in the art will notice and appreciate that the U-shaped structural member's 1502 aforementioned features apply just the same even without any structural members 1501 or recesses 1510 while still accomplishing all the goals, features, and advantages of the present invention.

Now referring to FIG. 16B, the structural member lock slot 1601 is shown being formed through the structural member 1501. The structural member 1501 is preferably adapted to be positioned on the upper portion of the passageway so that the structural member lock slot 1601 is aligned with a lock slot formed in the body member 201. The alignment of the structural member lock slot 1601 with the lock slot formed in the body member 201 advantageously allows for rotatable movement of the locking arm 601 between the locked position where the locking arm is engaged with the U-shaped structural member lock slot 1505, the structural member lock slot 1601 and the lock slot formed through the body member 201, and the unlocked

12

position where the locking arm 601 is disengaged from the U-shaped structural member lock slot 1505, the structural member lock slot 1601 and the lock slot formed through the body member 201.

Now referring back to FIG. 1A, the door panel 105 in a main body member 101 may have a door panel receiving slot that may be configured to allow for the mating engagement of the locking arm 601 when the lock member 104 is rotatably engaged or disengaged. The door panel 105 includes a similar configuration for the U-shaped structural member 1502, the recess 1501, the lock slots 1505 and 1601 and the through channels 1503 and 1504.

Now referring back to FIGS. 7, 10, 12, and 16B, the pet travel door frame lock slot 1203, the structural member lock slot 1601, the U-shaped structural member lock slot 1505, the upper security panel lock slot 1104, the upper security panel structural member lock slot 1002, the security panel body member lock slot 701, and/or a door panel lock slot (not shown) or body member lock slot (not shown) may be positioned to align with one another to allow for movement and engagement and disengagement of the locking arm 601 of the lock member 104.

Now referring additionally to FIG. 2, the locked position of the lock member 104 is defined by the locking arm 601 of the lock member 104 being positioned to engage the pet travel door frame lock slot 1203, the structural member lock slot 1601, the U-shaped structural member lock slot 1505, the upper security panel lock slot 1104, the upper security panel structural member lock slot 1002, the security panel body member lock slot 701, and/or the door panel lock slot (not shown) or body member lock slot (not shown).

The unlocked position of the lock member 104 is defined by the locking arm 601 being positioned to disengage the pet travel door frame lock slot 1203, the structural member lock slot 1601, the U-shaped structural member lock slot 1505, the upper security panel lock slot 1104, the upper security panel structural member lock slot 1002, the security panel body member lock slot 701 and/or the door panel lock slot (not shown) or body member lock slot (not shown).

The pet travel door frame lock slot 120 the structural member lock slot 1601, the U-shaped structural member lock slot 1505, the upper security panel lock slot 1104, the upper security panel structural member lock slot 1002, the security panel body member lock slot 701, and/or a door panel lock slot (not shown) or body member lock slot (not shown) may be configured to be at an angle such that when the locking arm 601 of the lock member 104 is rotatably moved to the locked position the locking arm 601 may encounter increased resistance as it is increasingly rotatably turned, and may experience a greater amount of friction as the locking arm 601 is rotatably moved to the locked position. The angle referred to above is an angle that is off-center from an imaginary vertical plane traveling between ends of the lock slots 1505 and 1601. In other words, the locking arm 601 may be configured so that when it is rotated into the locked position, the locking arm 601 is off-center from the imaginary plane to increase resistance and provide for a stronger locked position.

Now referring back to FIGS. 1A, 1B, 9, 11, 12, 15A, and 17B, the main body member or body receiving channels 1512, the pet travel door frame through channels 1202, the seal member through channels 1103, and/or the U-shaped structural member through channels 1504 may be positioned to align with one another and the structural post members 901 and allow for the structural post members 901 to be matingly positioned within them when the security panel 502 is placed to cover the pet travel door 301.

Now referring additionally to FIG. 10, the structural post member 901 on the lower security panel structural member 1003 may be configured to comprise of an elongated flat plate and/or cylindrical poles. The main body member or body receiving channels 1512, the pet travel door frame through channels 1202, the seal member through channels 1103, and/or the U-shaped structural member through channels 1504 may be configured to comprise of a channel to accept an elongated flat plate that is used as the structural post members 901, and/or the structural post members 601 as illustratively shown in FIG. 10 as cylindrical poles.

Referring now additionally to FIG. 19, the present invention includes a kit 1900 to retrofit an existing door 100 to include a pet travel door 301. The kit 1900 may include a container 1902, a pet travel door 301 carried by the container 1902, and a structural member 1501 carried by the container 1902. The kit 1900 may also include a U-shaped structural member 1502 carried by the container 1902 and at least one of an adhesive 1904, an adhesive double sided tape 1906, at least one screw 1908, and at least one bolt 1910 carried by the container 1902. The pet travel door 301 is adapted to be affixed within a passageway 304 formed through a portion of the existing door 100. The pet travel door 301 is also adapted to be affixed within the passageway 304 using at least one of the adhesive 1904, the adhesive double-sided tape 1906, the at least one bolt 1910, and the at least one screw 1908.

As discussed in greater detail above, the structural member 1501 and the U-shaped structural member 1502 may have at least one through channel formed through a portion thereof. The at least one through channel may be adapted to be align with a through channel formed in the existing door 100 adjacent to at least one of the top and the bottom of the passageway 304.

The kit 1900 may also include a security panel 502 carried by the container. The security panel 502 may be configured to engage with portions of the pet travel door 301. The security panel 502 may include a security panel body member 102 having a front face and a back face and a lower security panel structural member 1003 connected to a bottom portion of the security panel body member 102 and having a pair of structural post members 901 extending outwardly therefrom. The security panel 502 may also include a lock member 104 carried by a top portion of the security panel body member 102. As described in greater detail above, the lock member 104 is rotatably moveable between a locked position and an unlocked position. The security panel 502 may also include an upper security panel structural member 1001 affixed to a top of the security panel body member 102. The upper security panel structural member 1001 has an upper security panel lock slot 1002 formed therein and positioned to align with the lock slot formed in the existing door 100.

The kit 1900 may further include a seal member 501 carried by the container 1902. The seal member 501 is adapted to be positioned adjacent an outer peripheral portion of the security panel body member 102. The seal member 501 may also have a lock slot 1104 formed therein and positioned to align with the lock slot formed in the existing door 100.

Now referring to FIGS. 23A-24, an embodiment of the present invention may include the security panel 502 being hingedly attached to an inside facing portion of the pet travel door frame 302 by a hinge member 1702, defined as a hinged pet travel door system 1700. In the system 1700, the hinge member 1702 may be positioned on a right-hand side of the security panel 502, the pet travel door 301, and/or the pet travel door frame 302. Those skilled in the art will notice and

appreciate that the hinge member 1702 may be positioned in a number of locations on the security panel 502, the pet travel door 301, and the pet travel door frame 302 while still accomplishing all the goals, features, and advantages of an embodiment of the present invention such as, for example, the left-hand side of the security panel 502, the pet travel door 301 and/or the pet travel door frame 302. The hinged member 1702 may be attached to the security panel 502 and the pet travel door frame 302 via rivets, screws, bolts, nails, adhesive, and/or cement. For example, rivet members 1703 are illustratively shown in FIG. 23C fixedly attaching the hinge member 1702 to the security panel 502 and to the pet travel door frame 302.

In the system 1700, the security panel 502 may be configured to be rotatably moved between an opened position and/or a closed position by use of the hinge member 1702. The opened position of the security panel 502 may be defined as when the security panel 502 is rotatably moved so that it is not covering the pet travel door 301 and the closed position of the security panel 502 may be defined as when the security panel is rotatably moved so that it is covering the pet travel door 301.

The system 1700 may include the pet travel door lock slot 1203 being positioned on an inner facing side of the pet travel door frame 302 that is opposite of the hinge member 1702, as illustratively shown in FIG. 23B. The system 1700 may further include an alternate seal member 501' that may be attached on a perimeter of the security panel 502. The security panel 502 may further include the lock member 104 being positioned on a portion of the security panel 502 that is on an opposing side from where the hinge member 1702 is attached to the security panel 502. The lock member 104 may be configured to have the same features and functionality as mentioned above and further below herein when used with a hingedly connected security panel 502. The seal member lock slot 701 may be positioned on the alternate seal member 501' on the same side of the security panel 502 as where the lock member 104 is positioned on the security panel 502 such that the seal member lock slot 701 is positioned to allow for the rotatable movement of the lock member 104 and the locking arm 601.

Now referring specifically to FIG. 24, the system 1700 configuration may also include a second alternate seal member 501" that may be attached to an inside facing side 45 of the security panel 502. The second alternate seal member 501" may also be positioned on the security panel 502 such that the second alternate seal member 501" is overlaying the reinforcement member 602. The second alternate seal member 501" may be positioned on the security panel 502 so that it may be about the same as the perimeter of the security panel 502 and may comprise of rubbers, plastics, composites, and/or elastics either in whole or in part, and either in a homogeneous or heterogenous combination. The second alternate seal member 501" may be configured to create a seal against the pet travel door 301 and/or pet travel door frame 302 when the security panel 502 is in the closed position as illustratively shown in FIG. 23A.

All of the above mentioned and unmentioned, members, components, and pieces of the embodiments of the present invention may be connected, affixed, and or attached by one or more of bolts, nuts, screws, nails, adhesive, adhesive tape, adhesive double sided tape, cement, epoxy, glue, grout, tar, welding, and/or any other way of connecting/affixing/attaching the members and components of the present invention as understood by those skilled in the art. Those skilled in the art will notice and appreciate that the members and components of the present invention may be attached in a

15

number of ways and still accomplish all the goals, features, and advantages of the present invention. Preferably, in the embodiments of the present invention any fasteners used to attach, affix, and/or connect the pieces, members, and/or components of the present invention such as, without limitation, nuts, bolts, screws, and/or nails are only accessible from an inside facing side of the present invention. 5

Embodiments of the present invention may also be adapted to be installed into walls, windows, glass doors, panels, and other surfaces rather than in a door 100 as 10 described herein while still accomplishing all the goals, features, and advantages of the present invention.

Some of the illustrative aspects of the present invention may be advantageous in solving the problems herein described and other problems not discussed which are 15 discoverable by a skilled artisan.

While the above description contains much specificity, these should not be construed as limitations on the scope of any embodiment, but as exemplifications of the presented embodiments thereof. Many other ramifications and variations are possible within the teachings of the various embodiments. While the invention has been described with reference to exemplary embodiments, it will be understood by those skilled in the art that various changes may be made, and equivalents may be substituted for elements thereof 20 without departing from the scope of the invention. In addition, many modifications may be made to adapt a particular situation or material to the teachings of the invention without departing from the essential scope thereof. Therefore, it is intended that the invention not be limited to the particular embodiment disclosed as the best or only mode contemplated for carrying out this invention, but that the invention will include all embodiments falling within the scope of the appended claims. Also, in the drawings and the description, there have been disclosed exemplary embodiments of the invention and, although specific terms may have been employed, they are unless otherwise stated used in a generic and descriptive sense only and not for purposes of limitation, the scope of the invention therefore not being so limited. Moreover, the use of the terms first, second, etc. do not denote any order or importance, but rather the terms first, second, etc. are used to distinguish one element from another. Furthermore, the use of the terms a, an, etc. do not denote a limitation of quantity, but rather denote the presence of at least one of the referenced item. 25

Thus the scope of the invention should be determined by the appended claims and their legal equivalents, and not by the examples given.

What is claimed is:

1. A door having an integrated pet travel door, the door 50 comprising:
  - a main body member having at least one door panel, wherein the at least one door panel includes a front face and a back face, and wherein the pet travel door is carried by one of the at least one door panel;
  - a passageway formed in the one of the at least one door panel of the main body member, the passageway being defined as having a top, a bottom, and side portions extending between the top and the bottom;
  - a first recess formed within the top of the one of the at 55 least one door panel of the main body member adjacent the top of passageway, and extending latitudinally substantially the top of the passageway;
  - a second recess formed within the one of the at least one door panel of the main body member adjacent the bottom of the passageway, and extending latitudinally substantially the bottom of the passageway;

16

a plurality of structural members that are each substantially the same shape as one of the recesses, and are each—matingly engaged with one of the recesses; and a respective number of U-shaped structural members that are substantially the same length as one of the recesses, wherein each of the U-shaped structural members are positioned to overly one of the recesses, and matingly engage a portion of the door panel surrounding the one of the recesses;

at least one through channel formed through a portion of the structural members and the U-shaped structural members;

wherein the first recess and the second recess are substantially the same size and shape;

wherein the main body member has a respective at least one receiving channel formed therein adjacent to at least one of the top of the passageway and the bottom of the passageway;

wherein the through channels formed in the structural members and the U-shaped structural members are positioned to align with one another and with the respective receiving channels formed in the main body member;

wherein the through channels and the receiving channels are configured to receive a portion of a security panel therein.

2. The door of claim 1 wherein the structural members are secured to the recesses using at least one of adhesive and double-sided adhesive tape; and wherein the U-shaped structural members are secured to the portion of the door panels adjacent the recess using at least one of adhesive and double-sided adhesive tape. 30

3. The door of claim 1 wherein the pet travel door includes a pet travel door frame that is affixed to the one of the at least one door panel; wherein the shape of the pet travel door frame is substantially similar to the shape of the passageway formed in the one of the at least one door panel; and wherein the pet travel door frame is secured to the one of the at least one panel adjacent to at least one of the top, bottom and side portions of the passageway using fasteners that are at least one of screws and bolts; and wherein the fasteners are only accessible from one side of the at least one door panel. 40

4. The door of claim 1 wherein the security panel further 45 comprises:

a security panel body member having a front face and a back face;

a lower security panel structural member connected to a bottom portion of the security panel body member and having a pair of structural post members extending outwardly therefrom;

a lock member carried by a top portion of the security panel body member, the lock member being rotatably moveable between a locked position and an unlocked position;

wherein the locked position of the lock member is defined by a locking arm of the lock member being positioned to engage a lock slot formed adjacent the top of the passageway extending through a portion of one of the structural members, through a portion of one of the U-shaped structural members, and within a portion of the one of the at least one door panels, and the unlocked position of the lock member is defined by the locking arm being positioned to disengage the lock slot. 55

5. The door of claim 4 wherein the security panel further comprises an upper security panel structural member affixed to a top of the security panel body member; wherein the

upper security panel structural member has an upper security panel lock slot formed therein and positioned to align with the lock slot.

6. The door of claim 4 further comprising a seal member positioned adjacent an outer peripheral portion of the security panel body member; wherein the seal member has a seal member lock slot formed therein and positioned to align with the lock slot.

7. The door of claim 6 wherein the lock member further comprises a key lock; wherein the key lock is moveable between an unlocked and a locked position; wherein when the key lock is in the locked position, the lock member is not moveable between the locked and the unlocked position; and wherein when the key lock is in the unlocked position, the lock member is moveable between the locked and the unlocked position.

8. A door panel having an integrated pet travel door for installing into an existing door, the door panel comprising:

a body member; wherein the body member includes a front face and a back face; and wherein the pet travel door is carried by the body member;

a body frame member affixed to an outer peripheral portion of the body member;

a passageway formed in the body member, the passageway being defined as having a top, a bottom, and side portions extending between the top and the bottom;

a first recess formed within the top of the body member adjacent the top of the passageway, and extending latitudinally substantially of the top of the passageway; a second recess formed within the body member adjacent the bottom of the passageway, and extending latitudinally substantially the bottom of the passageway;

a plurality of structural members that are each substantially the same shape as one of the recesses, and are each matingly engaged with one of the recesses; a respective number of U-shaped structural members that are substantially the same length as one of the recesses, wherein each of the U-shaped structural members are positioned to overly one of the recesses, and matingly engage a portion of the body member surrounding the one of the recesses; and

at least one through channel formed through a portion of the structural members and the U-shaped structural members; wherein the first recess and the second recess are substantially the same size and shape; wherein the body member has a respective at least one receiving channel formed therein adjacent to at least one of the top of the passageway and the bottom of the passageway; and

wherein the through channels formed in the structural members and the U-shaped structural members are positioned to align with one another and with the respective receiving channels formed in the body member; wherein the through channels and the receiving channels are configured to receive a portion of a security panel therein.

9. The door panel of claim 8 wherein the structural members are secured to the recesses using at least one of adhesive and double-sided adhesive tape; and wherein the U-shaped structural members are secured to the portion of the body member using at least one of adhesive and double-sided adhesive tape.

10. The door panel of claim 8 wherein the pet travel door includes a pet travel door frame that is affixed to the body member; wherein the shape of the pet travel door frame is

substantially similar to the shape of the passageway formed in the body member; and wherein the pet travel door frame is secured to body member adjacent to at least one of the top, bottom and side portions of the passageway using fasteners that are at least one of screws and bolts; and wherein the fasteners are only accessible from one side of the door panel.

11. The door panel of claim 8 wherein the security panel further comprises:

a security panel body member having a front face and a back face;

a lower security panel structural member connected to a bottom portion of the security panel body member and having a pair of structural post members extending outwardly therefrom;

a lock member carried by a top portion of the security panel body member, the lock member being rotatably moveable between a locked position and an unlocked position;

wherein the locked position of the lock member is defined by a locking arm of the lock member being positioned to engage a lock slot formed adjacent the top of the passageway extending through a portion of one of the structural members, through a portion of one of the U-shaped structural members, and within a portion of the body member, and the unlocked position of the lock member is defined by the locking arm being positioned to disengage the lock slot.

12. The door panel of claim 11 wherein the security panel further comprises an upper security panel structural member affixed to a top of the security panel body member; wherein the upper security panel structural member has an upper security panel lock slot formed therein and positioned to align with the lock slot.

13. The door panel of claim 11 further comprising a seal member positioned adjacent an outer peripheral portion of the security panel body member; wherein the seal member has a seal member lock slot formed therein and positioned to align with the lock slot formed in the body member.

14. The door panel of claim 12 wherein the lock member further comprises a key lock; wherein the key lock is moveable between an unlocked and a locked position; wherein when the key lock is in the locked position, the lock member is not moveable between the locked and the unlocked position; and wherein when the key lock is in the unlocked position, the lock member is moveable between the locked and the unlocked position.

15. A kit to retrofit an existing door to include a pet travel door, the kit comprising:

a container;

a pet travel door carried by the container;

a plurality of structural members carried by the container; a respective number of U-shaped structural members carried by the container; and

at least one of an adhesive, an adhesive double-sided tape, at least one screw, and at least one bolt carried by the container;

wherein the pet travel door is adapted to be affixed within a passageway formed through a portion of the existing door, the passageway being defined as having a top, a bottom, and side portions extending between the top and the bottom;

wherein the structural members are adapted to be matingly engaged with at least one of a first recess formed within the top of the existing door that is adjacent the top of the passageway and that is extending latitudinally substantially the top of the passageway, and with a second recess formed within the existing door that is

19

adjacent the bottom of the passageway and that also is extending latitudinally substantially the bottom of the passageway;
 wherein, the U-shaped structural members are adapted to be positioned to overly one of the recesses, and are adapted to be matingly engaged with a portion of the existing door surrounding the one of the recesses; and wherein the pet travel door is adapted to be affixed within the passageway using at least one of the adhesive, the adhesive double-sided tape, the at least one bolt, and the at least one screw; and
 wherein, the structural members and the U-shaped structural members have at least one through channel formed through a portion thereof;
 wherein, the at least one through channel is adapted to be align with at least one receiving channel formed within the existing door that are adjacent to at least one of the top and bottom of the passageway; and wherein the through channels and the receiving channels are configured to receive a portion of a security panel therein.

16. The kit of claim **15** wherein the security panel comprises:

a security panel body member having a front face and a back face;
 a lower security panel structural member connected to a bottom portion of the security panel body member and having a pair of structural post members extending outwardly therefrom;
 a lock member carried by a top portion of the security panel body member, the lock member being rotatably moveable between a locked position and an unlocked position;

5

10

15

20

25

30

20

wherein the locked position of the lock member is defined by a locking arm of the lock member being positioned to engage a lock slot formed adjacent the top of the passageway within a portion of one of the structural members, a portion of one of the U-shaped structural members, and within a portion of the existing door adjacent to the top of the passageway, and the unlocked position of the lock member is defined by the locking arm being positioned to disengage the lock slot.

17. The kit of claim **16** wherein the security panel further comprises an upper security panel structural member affixed to a top of the security panel body member; wherein the upper security panel structural member has an upper security panel lock slot formed therein and positioned to align with the lock slot.

18. The kit of claim **17** further comprising a seal member carried by the container; wherein the seal member is adapted to be positioned adjacent an outer peripheral portion of the security panel body member; wherein the seal member has a seal member lock slot formed therein positioned to align with the lock slot formed.

19. The kit of claim **18** wherein the lock member further comprises a key lock; wherein the key lock is moveable between an unlocked and a locked position; wherein when the key lock is in the locked position, the lock member is not moveable between the locked and the unlocked position; and wherein when the key lock is in the unlocked position, the lock member is moveable between the locked and the unlocked position.
